UNITED STATES PATENT OFFICE.

FRANK W. FRIES AND WILLIAM J. FRIES, OF CARLINVILLE, ILLINOIS.

COUPLING FOR MINING CARS.

Application filed March 3, 1922. Serial No. 540,760.

To all whom it may concern:

Be it known that we, FRANK W. FRIES and WILLIAM J. FRIES, citizens of the United States, residing at Carlinville, Macoupin County, Illinois, have invented new and useful Couplings for Mining Cars, of which the following is a specification.

This invention relates to couplers for mining cars.

10 An object of the invention is to provide an improved coupler for use on mining cars and the like that overcomes or eliminates many of the objections or deficiencies that are characteristic of the couplers in general use in connection with mining cars.

Another object of the invention is to provide an improved coupler designed and arranged so that it may be easily operated to couple or uncouple the cars irrespective of 20 whether the cars are upon a straight or a curved track when the coupler is operated for the purpose mentioned.

Another object of the invention is to provide an improved coupler for use in connection with mining cars that is characterized by proper elasticity needed in couplers of this type; and that is further characterized by a capability of free movement, permitting the cars to make sharp turns without 30 exerting improper strains upon the cars or the coupler.

Numerous other objects and advantages of the invention will appear from the following description, reference being made to 35 the drawing, in which—

Fig. 1 is a view showing our improved coupler in actual use, certain of the parts being shown in section.

Fig. 2 is an inverted plan view of the 40 coupler with parts broken away.

Fig. 3 is a detailed sectional view showing certain of the improved features of the invention.

In the embodiment of the invention 45 shown, an archway support for one of the coupling members is rigidly attached to the under-structure or frame of the car to which the coupler is to be applied. Said support comprises a casting 1 rigidly secured to the 50 car frame or body by bolts 2 and provided with a pair of spaced flanges 3. The spaced flanges 3 curve and constitute a supporting track for the movable block or body 4 which in cross-section is substantially I-shaped,

having the upper flanges thereof bearing 55 upon the flanges 3 and the lower flanges thereof engaging below the flanges 3, leaving the flanges 3 extending between the upper and lower flanges of said body or block. The track formed by the flanges 3 is 60 arcuate, as clearly shown in Fig. 2, and the supporting block or body 4 is movable thereon toward each side of the car. An integral connection 5 unites the track flanges 3 at one end, the opposite end of the track 65 being open to permit insertion and withdrawal of the block or body 4. A removable abutment 6 which may be in the form of a bolt, as shown, is secured to the opposite end of the track to prevent the block or body 4 70 from moving off of the support. Said block or body is freely movable between the abutments 5 and 6.

A coupler bar 7 has a recess 8 in its underside, the side walls of which converge upwardly so that in cross-section said recess is A-shaped. A block 9 seats within the recess 8 having its side walls beveled to match the side walls of the recess, forming a kind of swivel support for the coupling bar. The 80 block 9 is of less length than the recess 8 so that there is no contact between the ends of the block and the end walls of the recess. A supporting pin 10 passes through the block 9 and through a slot 11 in the coupling 85 bar 7 and is supported by the supporting block 4. The slot 11 is longer than the diameter of the pin 10 so that the coupling bar is capable of certain longitudinal movement, which movement is limited by the 90 length of said slot. The inner end of the bar 7 has a weight 12 thereon which is sufficient to uphold the outer end of the coupling bar. The outer end of the coupling bar 7 comprises a half-round extension 13, against 95 which a matching half-round extension 14 of the coupling hook fits. The outer end of the extension 13 has a collar 15 rigid therewith while the inner end of the matching member 14 has a collar 16 rigid with it. A 100 strong coiled spring 17 of the expansion type encircles the two members 13 and 14 between the collars 15 and 16.

A hook 18 on the end of the hook member has its outer edge inclined or sloping toward 105 the car support which is part of the coupling so as to provide an inclined surface to facilitate movement of this coupling mem-

ber and to assure proper functioning thereof automatically and as an incident to the movement of one car toward another.

As shown, the cooperating coupling member is supported by the adjacent end of the other car and comprises a downwardly and inwardly inclined flange 19 integral with the bumper 20. The outer surface of the flange 19 is inclined downwardly and inwardly so that when it bumps against the outer inclined surface of the hook 18 the hook will be lowered until the flange 19 passes over it after which the weight 12 will raise the hook 18 behind the flange 19, thus uniting the coupling members. The car supporting the coupling bar is equipped with a bumper 21 for obvious purposes.

From the foregoing it will be seen that the coupler is capable of free movement and that it will function properly, irrespective of the curvature of the track upon which the cars operate; that is, the coupler will function perfectly upon a straight track or upon a track with sharp curves with equal facility. It functions properly without exerting strains upon the car structure or upon the coupler. The strains are not increased materially at any time.

The invention also comprises means for releasing the coupler to detach one car from another. In the embodiment of the invention shown the releasing means comprises an arcuate bail 22 extending across the operating coupler member and having supporting arms 23 mounted in brackets 24 at opposite sides of the car. The arms 23 are provided with handles 25 whereby the bail may be conveniently operated to release the coupler. Springs 26 connect the arms 23 with fixed parts of the car and support the bail 22 so that normally it does not exert any weight or pressure against the coupler. In order to release the coupler it is only necessary to operate the bail device in opposition to the power of the springs 26, and since the handles are located at the sides of the car it is unnecessary for the person to pass between or to reach between the cars. Thus, the device is made perfectly safe and can be operated and used without any danger whatever.

From the foregoing it will be seen that our invention obtains all of its intended objects and purposes, is perfectly safe in operation, and meets all of the requirements of safety and utility. It is perfectly plain that the invention may be varied in numerous particulars without departure from the nature and principle thereof. Accordingly, we do not restrict ourselves unessentially, but what we claim and desire to secure by Letters Patent is:—

1. A coupler for mining cars, comprising a support secured to the underside of the car, a member mounted on said support for

lateral sliding movements toward each side of the car, a vertical pivot element supported by said member, a block pivotally supported by the lower end of the pivot member, and a coupler device supported by said block and capable of oscillation vertically relative thereto. 70

2. A coupler for mining cars, comprising a support secured to the underside of the car, a member mounted on said support for lateral sliding movements toward each side of the car, a vertical pivot element supported by said member, a block pivotally supported by the lower end of the pivot member for horizontal turning movements, 80 a coupler device supported by said block and capable of oscillation vertically relative thereto, and means for oscillating said coupler device. 75

3. A coupler for mining cars, comprising a support secured to the underside of the car, an arcuate track in connection with said support, a member mounted on said track for lateral sliding movements toward each side of the car, a vertical pivot extending 90 downwardly from said member, a block pivotally supported by said pivot for horizontal turning movements, and a coupler device supported by said block and capable of oscillation vertically relative thereto. 95

4. A coupler for mining cars, comprising a support secured to the underside of the car, an arcuate track in connection with said support, a member mounted on said track for lateral sliding movements toward each side of the car, a pivot extending downwardly from said member, a block pivotally supported by said pivot for horizontal turning movements, a coupler device supported by said block and capable of oscillation vertically relative thereto, and manual means operable from the side of the car for oscillating the coupler device. 100 105

5. A coupler for mining cars, comprising an arcuate support secured to the under side of the car, a member mounted on said support for lateral sliding movements toward each side of the car, a vertical pivot in connection with said member, a block pivotally supported by said pivot below said member for horizontal turning movements, a bar having an elongated recess therein receiving said member and having a slot through which said pivot extends permitting said bar to move longitudinally and to oscillate vertically relative to said member, a coupling element, and an elastic connection between said coupling element and said bar. 110 115

6. A coupler for mining cars, comprising an arcuate support secured to the under side of the car, a member mounted on said support for lateral sliding movements toward each side of the car, a vertical pivot in connection with said member, a block pivotally 120 125

supported by said pivot below said member for horizontal turning movements, a bar having an elongated recess therein receiving said member and having a slot through 5 which said pivot extends permitting said bar to move longitudinally and to oscillate vertically relative to said member, a coupling element, an elastic connection between

said coupling element and said bar, a weight in connection with the inner end of said bar 10 counterbalancing said coupling element, and a device operable from either side of the car for imparting vertical oscillating movements to said coupling element and said bar.
